UNITED STATES PATENT OFFICE.

HARUE HIRAKAWA, OF SAN DIEGO, CALIFORNIA.

STRING-CUTTING RING.

1,309,325.

Specification of Letters Patent.

Patented July 8, 1919.

Application filed March 19, 1918. Serial No. 223,430.

To all whom it may concern:

Be it known that I, HARUE HIRAKAWA, a subject of the Emperor of Japan, residing at San Diego, in the county of San Diego 5 and State of California, have invented certain new and useful Improvements in String-Cutting Rings, of which the following is a specification.

My invention relates to a ring to be worn 10 on the finger by clerks in stores and the like for cutting string, when doing up packages and the objects of my invention are:

First, to provide a ring resembling the conventional ornamental finger ring to be 15 worn on the finger, which supports a knife for severing the string at any place desired. Second, to provide a string cutting ring of this class with oppositely disposed severing edges so that the string may be severed by 20 pulling it in either direction as desired. Third, to provide a ring of this class in which the string cutting knife is so positioned that it is not liable to cut the wearer or others coming in contact with the ring, 25 and fourth, to provide a string cutting ring of this class which is very simple and economical of construction, durable, easy to operate, and which will not readily deteriorate or get out of order.

With these and other objects in view as 30 will appear hereinafter, my invention consists of certain novel features of construction, combination and arrangement of parts and portions as will be hereinafter described in detail and particularly set forth in the appended claims, reference being had to the accompanying drawings and to the characters of reference thereon, which form a part of this specification, in which:

Figure 1, is a side elevational view of the ring: Fig. 2, is an edge view thereof: Fig. 3, is a sectional view through 3—3 of Fig. 2, looking in one direction: Fig. 4, is a similar view, looking in the opposite direction: Fig. 5, is a top view of said ring and Fig. 6, is a sectional view through 6—6 of Fig. 1.

Similar characters of reference refer to similar parts and portions throughout the 50 several views of the drawings.

The ring member 1, knife member 2, and torsion spring 3, constitute the principal parts of my string cutting ring.

The ring member 1, is shaped similar to 55 the conventional ornamental ring, and may be made in different sizes to fit the finger

of the operator. It is provided on its top side with an enlarged portion 1^a, in the middle of which is a downwardly enlarging groove 1^b, leaving upwardly extending projecting portions 1^c and 1^d. In the portion 1^c is pivotally mounted the knife member 2, by means of the pin 2^a, this knife member 2, is bifurcated and between the two members on the pin 2^a is a torsion spring 3, 60 the one end of which engages a portion of the portion 2^a and the other end engages the lower surface of the knife 2, thus tending to hold the free end of the knife 2 upwardly against a projection 1^e in the portion 1, as shown best in Fig. 6. This knife blade 2, may be depressed to permit the string to enter the slot 1^b under the knife and then either end of the string may be brought over either edge of the knife and 65 the string severed by the sharpened edge 2^c. It will be here noted that there is a cut-away portion 1^f, forming a notch in the side 1^d of about the same width as the knife blades so that when the knife is in its normal position the edges of the knife engage the sides of the notch 1^f, making it rigid against 70 pressure from either side. It will be here noted that the sides of the ring at 1^g is knurled to permit the string from slipping 75 off.

Though I have shown and described a particular construction, combination and arrangement of parts and portions, I do not wish to be limited to this particular 80 construction combination and arrangement but desire to include in the purview of my invention the construction, combination, and arrangement substantially as set forth in the appended claims.

It is obvious that with this construction of ring there is provided a means for readily severing a string, the string being pressed down against the knife 2, depressing the same so that the string passes the free edge 100 of the knife into the slot 1^b, after which either end of the string may be brought up against the sharp edge of the knife and severed.

Having thus described my invention, what 105 I claim as new, and desire to secure by Letters Patent, is:

1. In a device of the class described, a band ring provided with an enlarged portion with an inwardly enlarging circumferential 110 slot therein, a knife with oppositely disposed cutting edges pivotally mounted in one side

portion, and extending over said slot and its opposite edge engaging the opposite side which serves as a stop and a torsion spring engaging said knife and the side in which 5 said knife is pivoted tending to hold the free side of said knife outwardly in engagement with the stop side.

2. In a device of the class described, a band ring provided with an enlarged portion 10 with an inwardly enlarging circumfer-

ential slot therein, a knife with oppositely disposed cutting edges pivotally mounted in one side portion and yieldable inwardly, and a stop on the opposite side portion with which said knife engages in its outward ¹⁵ movement.

In testimony whereof, I have hereunto set my hand at San Diego, California, this 14th day of March, 1918.

HARUE HIRAKAWA.

Copies of this patent may be obtained for five cents each, by addressing the "Commissioner of Patents Washington, D. C."
